CLAIM

The ornamental design for handheld emergency tool, as shown and described.

DESCRIPTION

FIG. 1 is a front perspective view of the handheld emergency tool;

FIG. 2 is a rear perspective view of the handheld emergency tool;

FIG. 3 is a front view of the handheld emergency tool;

FIG. 4 is a back view of the handheld emergency tool;

FIG. 5 is a left side view of the handheld emergency tool;

FIG. 6 is a right side view of the handheld emergency tool;

FIG. 7 is a top view of the handheld emergency tool;

FIG. 8 is a bottom view of the handheld emergency tool;

FIG. 9 is a front perspective view of the handheld emergency tool showing the antenna extended;

FIG. 10 is a rear perspective view of the handheld emergency tool showing the antenna extended; and,

FIG. 11 is a rear perspective view of the handheld emergency tool showing the crank extended and open.

The broken line showing of controls and control panel is for the purpose of illustrating environmental structure and forms no part of the claimed design.
